UNITED STATES PATENT OFFICE.

GEORGE PROBST, OF SARDIS, OHIO.

BOLTLESS RAIL-COUPING.

1,196,025.

Specification of Letters Patent. Patented Aug. 29, 1916.

Application filed May 11, 1916. Serial No. 96,835.

To all whom it may concern:

Be it known that I, GEORGE PROBST, a citizen of the United States, residing at Sardis, in the county of Monroe and State of Ohio, have invented certain new and useful Improvements in Boltless Rail-Couplings; and I do hereby declare the following to be a full, clear, and exact description of the invention, such as will enable others skilled in the art to which it appertains to make and use the same.

My invention relates to new and useful improvements in boltless rail couplings and more particularly to that class adapted to be used in securing railroad track rails together, and my object is to provide means for securing the meeting ends of the rails together.

A further object is to provide means for holding the ends of the rails together without the employment of bolts.

Other objects and advantages will be hereinafter set forth and more particularly pointed out in the accompanying specification.

In the accompanying drawings which are made a part of this application, Figure 1 is a perspective view of the meeting ends of two rails showing my improved form of coupling attached thereto. Fig. 2 is a perspective view of the coupling removed from the rails, and Fig. 3 is a transverse sectional view through the coupling and rail showing the manner of attaching the same to a tie.

Referring to the drawings in which similar reference numerals designate corresponding parts throughout the several views, 1 and 2 indicate the meeting ends of the rails such as are used in railroad construction, the web portions 3 of said rails having transversely disposed slots 4 therethrough, through which extend fingers 5 of a coupling member 6, said coupling member being of sufficient length to extend a distance to each side of the meeting ends of the two rails.

The coupling member 6 comprises a fish-plate section 7 which fits one face of the web of the rails, a horizontal section 8 which rests over one flange of the base 9 of the rail, a base section 10 which extends below the base of the rail and a flange 11 which projects upwardly along one edge of the base of the rail, said coupling member being substantially L-shape in cross section.

The fingers 5 extending laterally from the upper edge of the fish-plate section 7 are curved and extended upwardly so that when the free ends of the fingers are introduced into the slots 4 and the base section 10 swung to position below the base of the rail, said fingers will interlock with the face of the web of the rail on the side of the web opposite the fish-plate section 65 and as the fingers are so arranged as to make a close connection with the web of the rails and in view of the manner of engaging the base of the rail with the bottom portion of the coupling member, said rails and coupling member will be securely locked together without the employment of bolts or other interlocking means. To cause the fingers to more readily interlock with the slots 4, the upper walls of the slots may be rounded, as best shown in Fig. 3, and the coöperating portions of the fingers are formed concave to fit the rounded portions of the slots, while the outer faces of the fingers are likewise rounded so that they will readily move into or out of the slots when the coupling member is swung into or out of engagement with the base of the rail.

In addition to providing the base section 10 and flange 11 for interlocking with the base of the rail, said parts may be further locked into engagement with the base of the rail by forming tongues 12 on the upwardly extending edge of the flange 11, which tongues may be bent over the upper face of 90 the base 9 of the rail, after the coupling member has been properly positioned on the rails.

As shown in Fig. 1 of the drawings, notches 13 may be formed in the flange 11 for the reception of spikes 14 by means of which the rails and coupling member are secured to the tie 15, the spikes 16 being also engaged with the opposite edge of the coupling member as best shown in Fig. 3 of 100 the drawing.

In attaching my improved form of coupling member to the meeting ends of the rails, the ties immediately below the ends of the rails are moved laterally or displaced, 105 when the ends of the fingers 5 are introduced into the slots 4 and the base section of the coupling member swung downwardly until it is positioned below the base of the rail, when the ties are replaced below the 110 coupling member and the spikes driven into the tie until the heads of the spikes engage

the horizontal portion of the coupling member and the base of the rail opposite to the horizontal section and, if desired, the tongues 12 may be then bent over the face of the rail base, thus more securely locking the coupling member to the rail.

When a temporary coupling is desired for the meeting ends of the rails, the base section 10 and flange 11 may be dispensed with, the spikes 16 being depended upon for holding the coupling member in engagement with the base of the rails.

This form of coupling may be very cheaply constructed and yet rendered extremely strong and durable and it may be forged or otherwise constructed from one piece of metal. It will likewise be seen that the coupling can be very quickly attached to or disengaged from the rails as it does not require the employment of bolts for locking the same in engagement with the rails and it will likewise be seen that when the coupling member is properly engaged with the rails, said rails will be held rigidly in engagement with each other.

What I claim is:—

1. In a rail coupling member, the combination with a pair of rails having slots therethrough, of a coupling member comprising a fish-plate section, a horizontal section integral therewith, a base section in-

tegral with the horizontal section, a flange integral with the base section, tongues on said flange adapted to be extended over the base of the rail, and curved fingers at the outer edge of the fish-plate section adapted to extend through said slots of the rails and interlock with the rails.

2. In a coupling member for rails, the combination with the meeting ends of a pair of rails, the webs of said rails having transversely disposed slots, the upper walls of which are rounded, of a coupling member comprising a fish-plate section, curved fingers adapted to extend through said slots and interlock with the webs of the rails, said fingers having concavities to coöperate with the rounded walls of the slots, a horizontal section integral with the fish-plate section, a base section integral with the horizontal section, and a vertically extending flange at the free edge of the base section, said horizontal section, base section and flange forming a seat for the base of the rail.

In testimony whereof I have signed my name to this specification in the presence of two subscribing witnesses.

GEORGE PROBST.
